UNITED STATES PATENT OFFICE.

BERNARD E. BECKER, OF BOSTON, ASSIGNOR TO J. ARTHUR NELSON, OF BROCKTON, MASSACHUSETTS.

PAPER-BOX MACHINE.

SPECIFICATION forming part of Letters Patent No. 315,461, dated April 14, 1885.

Application filed April 9, 1884. (No model.)

To all whom it may concern:

Be it known that I, BERNARD E. BECKER, a citizen of the United States, residing at Boston, in the county of Suffolk and State of Massachusetts, have invented certain new and useful Improvements in Paper-Box Machines; and I do hereby declare that the same are fully described in the following specification and illustrated in the accompanying drawings.

This invention relates to improvements in paper-box machines for the purpose of securing the sides to the bottom piece of pasteboard boxes without the need of scoring the sides at the place where they overlap the bottom piece, as will hereinafter be more fully shown and described, reference being had to the accompanying drawings, where—

Figure 1 represents a plan view of the improved machine. Fig. 2 represents a partial front elevation and central longitudinal section showing the various parts of the machine previous to creasing and securing the sides of the pasteboard box to its bottom piece. Fig. 3 represents a partial side elevation and longitudinal section showing the various parts of the machine in position while the side pieces of the pasteboard box are being united to the bottom piece. Fig. 4 represents a detail bottom plan view of the vertically-adjustable platen that carries the rollers for operating the creasers or folders. Fig. 5 represents a detail plan view of the lower bearing-plate for the vertically-movable rods by which the box is automatically removed from the machine after it is finished. Fig. 6 represents a detail front and sectional view of the pawl-plate and its spring-pawls for operating the discharge-rods and mechanism for removing the box when finished. Fig. 7 is a plan view of the box-corner-releasing mechanism, and Fig. 8 represents perspective views of the sides and bottom parts of the pasteboard box before being united together; and Fig. 9 represents a detail view of the pawls on the box-removing mechanism.

Similar letters refer to similar parts wherever they occur on the different parts of the drawings.

a is the hollow standard or post, to the upper end of which is secured firmly the hori-

zontal plate *b*, as shown. On the plate *b* rests loosely the box-former *c*, made of metal, in the shape of a hollow frame, the outside dimensions of which are equal, or nearly so, to the inside of the box that is being made. Such box-former may be made in one single piece or in two or more laterally expansive and adjustable parts. On the interior of the box-former *c* are made vertically-perforated ears *c' c'*, fitting loosely on the stationary guide-pins *b' b'*, that are secured to top of platen *b*, so as to serve as vertical guides for the box-former *c* during its vertical motion from and to the top of platen *b*, as will be further described. The former *c* is raised by means of treadle-lever *d*, that is hinged to the fulcrum-pin *d'* near the base-plate *a'* of the standard *a*, as shown in Fig. 3, such lever having the foot treadle *d''* at its forward end, and an adjustable counter-weight, *d''*, attached to its rear end, as shown in said Fig. 3.

To the treadle-lever *d*, within the post *a*, is hinged at *e'* the forked head *e''*, to which is attached the upwardly-projecting rod *e*. To the upper end of rod *e* is attached the forked head *e''*, as shown in Figs. 2 and 3, through the upper end of which projects the horizontal pin *e'*, the central part of which passes through the elongated slot *f'* in the connecting-rod *f*, the upper end of which is jointed at *f''* to the levers *g g*, as shown in Figs. 1 and 2. Each lever *g* is made to swing on its fulcrum-pin *g'*, located in bearings *b'' b''*, attached to or cast in one piece with plate *b*, as shown. Each lever *g* has in its outer end a lip, *g''*, adapted to work against a bar, *h*, secured to the inner end of box-former *c* by means of set-screw *h'*, as shown in Figs. 1, 2, and 3. Above bar *h*, to the inside of former *c*, are cast the corner ears or lugs, *c' c'*, that are tapped for the reception of the adjustable set-screws *c' c'*, the lower ends of which are made to abut against the upper side of bar *h*, to permit the latter to be adjusted vertically in relation to the box-former *c*, and thus to regulate the desired upward movement of the box-former when the foot-treadle *d''* is depressed by the operator.

To the ends and sides of the platen *b* are hinged the downwardly-projecting curved levers *i i i* by means of hinge or fulcrum pins *100*

$b^3 b^3 b^3 b^3$, passing through ears on the under side of platen b , as shown. The upper end of each lever i is cast in the form of a foot or rest, i' , to which is secured, by means of a set-screw, k' , the metal folder or creaser k , that has in its upper end the inwardly-projecting lip k'' , adapted to turn over and press downward the flaps of the box-sides onto the bottom piece of the box, and to secure such parts together by paste or glue or other adhesive substance, as will be further shown and described. Each holder k has a slot, k^3 , in its lower end, by means of which the set-screw k' said folder can be adjusted to and from the outside 15 of the box-former c according to the thickness of the material of which the box is being made. The levers i are swung outward to positions shown in Fig. 3 by means of the vertically-movable plate l , cast in one piece with sleeve 20 l' , that surrounds the hollow post a , and is made adjustable on the latter by means of pin e^4 , connected to forked head e^3 and treadle mechanism, as aforesaid. Said pin e^4 projects laterally through slots $a'' a''$, made on two opposite sides of standard a , and into perforations made in sleeve l' , as shown in Fig. 2.

To the under side of plate l are secured the bearings $l'' l''$, having horizontal pins l^3 passing through them, and on which are loosely journaled the respective anti-friction rollers l^4 , as shown in Figs. 2, 3, and 4. The rollers l^4 are adapted to lie in contact with the inside of the respective levers i , and to cause the latter to be swung outwardly when the sleeve l' and its 35 plate l are moved downward by the action of the treadle-lever $d d''$. Each lever i terminates in its lower end as a short linear or flat face, i'' , that is made parallel with the interior or upright face of its corresponding folder, k , and it is made for the purpose of permitting the 40 movable plate l and its sleeve l' to be drawn downward during a short time at the end of its stroke without expanding the levers i after the faces of the folders k have been brought 45 up against the outside of the sides of the pasteboard box surrounding the former c , and the folder-lips k'' brought down on top of the folded flaps of the box and the pasted bottom box-piece resting on top of box-former c , as shown 50 in Fig. 3, and during this latter part of the downward stroke of plate l its pin e^4 is brought in contact with the lower end of slot f' on the rod f , causing the latter to be pulled downward, and the box-former c to be raised and 55 pressed upward against the bottom of pasteboard box, its turned-over flaps, and the lips k'' on the folders k , by the connecting mechanism of levers $g g$ and bars $h h$, as described, as fully represented in Fig. 3, and thus causing 60 the turned-over flaps on the sides of the box to adhere to the pasted edges of the bottom piece previous to removing the box from the former.

The mechanism for automatically removing 65 and raising the box from the former c is carried out as follows: A short distance below the sleeve l' is secured on the hollow standard

a the bearing-plate m , as shown in Figs. 2, 3, and 5, provided with radial arms $m' m'$, having each a perforation in its outer end, into which 70 its respective vertical rod n is guided. The rods n are guided in their upper ends in perforated ears $b^4 b^4$, projecting outward from the corners of the upper platen, b , as shown in Figs. 1, 2, and 3. Each rod n has attached to its 75 upper end the vertically-adjustable socket n' , secured in place on rod n by means of set-screws n'' , or equivalent device, by means of which the socket n' may be adjusted up or down on rod n , according to the depth of the box that 80 is being made. The socket n' has also a horizontal perforation, in which is located the laterally-adjustable spindle o , secured to socket n' by means of set-screw n^3 or similar device. The inner end of spindle o has an eye, o' , to 85 which is hinged, by means of adjustable thumb nut and screw o'' , the forked corner rest, o^3 , as shown in Fig. 7, by which arrangement said rest o^3 may be adjusted up or down and to and from the box-former, according to the depth 90 and size of the pasteboard box that is being made, the underside of the latter resting loosely at the corners on the forked rests $o^3 o^3$ during the operation.

n^4 is a collar on each rod n , secured to it and 95 located above the radial arm m' , as shown in Figs. 2 and 3, such collar serving as a stop to limit the downward motion of each of the respective rods n against the respective radial arms m' . To two opposite sides of the movable plate l are secured the downwardly-projecting slotted bars $p p$, their lower ends being guided in cut-away parts $m'' m''$ on the lower stationary plate, m , as shown in Figs. 3 and 5. Each bar p has a vertical slot, p' , in which are 100 pivoted the pawls $q q$ on the pin p'' , as shown in Figs. 3, 9, and 6, and each pawl q has near its lower end a cut-away portion, q' , combined with an expansive spring, q'' , uniting said pawls $q q$ in such a manner that the lower and 105 upper ends of said pawls will automatically expand to the position shown in Fig. 9, when the plate l , sleeve l' , and bars $p p$ approach the lower end of its stroke, causing the upper ends of said pawls to project directly below the 110 levers $r r$, as shown in Fig. 9. Each lever r is hinged at r' to the standard or bracket m^3 , secured to or cast in one piece with lower plate, m , as shown in Figs. 2 and 5. The outer end of each lever r is forked at r'' , where it 115 embraces its respective rod n , as shown in said Figs. 2 and 5, and its outer end is loosely connected to rod n by means of pin n^5 , secured to rod n above the forked lever end r'' and collar n^4 below it, as shown in Fig. 2, and by this 120 means, after the treadle-lever d has been depressed and the bottom of the box united to its sides, as described, the bars $p p$, and with them the expansive pawls $q q$, are automatically caused to move upward as soon as the operator relieves the pressure on treadle d'' , and thereby causing the upper ends of pawls q to 125 act on levers $r r$ and their respective rods $n n$ to raise them upward, and with them the box-

corner supports $o^3 o^3 o^3 o^3$, by which arrangement the finished box is moved upward and disengaged from the box-former c . As the bars $p p$ reach their upper positions the pawls 5 $q q$ are automatically brought together to the position shown in Fig. 6 by the action of their lower projections, $q^3 q^3$, on the inside of the guides $m'' m''$ in plate m , causing the levers $r r$ to be released from said pawls $q q$, and 10 causing said levers $r r$, their rods $n n$, and box-corner supports $o^3 o^3$ to drop down to their normal lower positions, as represented in Fig. 2, and the machine is now ready for the reception of another box to be united in the 15 same manner, and so on.

In Fig. 8, s represents the continuous side portion of the pasteboard box with its upwardly-projecting flaps $s' s' s' s'$, in the usual manner, with this difference, however, that 20 no scoring is made at the junction of the main part of sides s and its flaps $s' s'$.

s'' represents the bottom piece that is to be pasted or glued to the bent-over flaps $s' s' s' s'$ by means of the mechanism and in the 25 manner as hereinabove described.

The operation of the machine is as follows: After having adjusted the corner supports, o^3 , to their respective positions on the rods n according to the depth of the sides s of box to 30 be made, I place the bottom pasteboard piece, s'' , on top of former c , and the continuous side pasteboard piece, s , around the former c in such a manner that the lower edges of the 35 pasteboard sides s shall rest loosely on the corner supports, o^3 , and the flaps $s' s'$ of the pasteboard sides project above the former c , as shown in Fig. 2. The inner sides of flaps s' , or a corresponding space on the outer edge of top of the bottom piece, s'' , having been 40 previously pasted or glued in the usual manner, I now depress the treadle d'' , causing the rollers $l^4 l^4$ to act on curved levers $i i$, and to force the folders $k k$ against the outside of the box s at the same time as the lips $k'' k''$ on 45 folders k impinge on pasteboard flaps s' and bend them over onto the top of the pasteboard piece s'' , as shown in Fig. 3, in which position

the box parts are held. By further depression of lever d the rod f is drawn downward, causing the former c to be forced upward by 50 the influence of levers $g g''$ and bars $h h$, and thereby causing the pasted edges of flaps $s' s'$ and bottom piece, s'' , to be still further pressed firmly together between top of former c and under side of lips $k'' k''$ on the folders $k k$, as 55 shown in Fig. 3. The operator now relieves the pressure on treadle d'' , by which the folders $k k''$ are automatically caused to expand to positions shown in Fig. 2, and the corner rests, $o^3 o^3$, to be automatically raised, as described, 60 for expelling the ready-made box, and afterward to return to their normal positions, (shown in Fig. 2,) when a new box is placed on the former c , to be acted on in the same manner, and so on.

What I wish to secure by Letters Patent, 65 and claim, is—

1. In a paper-box machine, the stationary support b , having former c , and hinged levers i , combined with folders $k k''$, made adjustable to and from the former c upon the levers i , substantially as set forth.

2. In a paper-box machine, the standard a , the platen b , box-former c , and hinged folders $k k''$, attached to levers $i i$, in combination 70 with vertically-movable plate l , its rollers l^4 , and intermediate connecting mechanism to the treadle-lever d , substantially as set forth and described.

3. In a paper-box machine, the herein-described box support and releasing mechanism, consisting of vertically-movable rods $n n$, laterally and vertically adjustable corner supports, $o^3 o^3$, levers $r r$, and automatic pawls $q q$, journaled to the vertically-movable bars 80 $p p$, and actuated by and connected to the treadle-lever d , substantially in a manner and for the purpose as set forth.

In testimony whereof I have affixed my signature in presence of two witnesses.

BERNARD E. BECKER.
